UNITED STATES PATENT OFFICE.

NORMAN R. SMITH, OF SAN FRANCISCO, CALIFORNIA.

AIRPLANE.

1,400,916.

Specification of Letters Patent. Patented Dec. 20, 1921.

Application filed June 30, 1920. Serial No. 392,919.

To all whom it may concern:

Be it known that I, NORMAN R. SMITH, a citizen of the United States, and a resident of the city and county of San Francisco, 5 State of California, have invented new and useful Improvements in Airplanes, of which the following is a specification.

My invention has for its objects an airplane which automatically maintains its 10 stability throughout all conditions, also a plane in which the greatest dimension is parallel with the line of flight, also one in which side slipping is prevented and wherein nose diving and tail spinning is prevented, thereby preventing the dangers incident 15 in planes heretofore.

Another object is the suspension of the car body or platform below the plane whereby a relatively level position of said body 20 is maintained.

A further object is the changing of the points of support of the car body or platform upon any distortion from the level of the plane surface.

25 Another object is the provision of a damper whereby the slowing up of the airplane on making a landing is attained.

Another object is to enable the plane to be operated from and to permit its landing in 30 a relatively narrow space, as a country road or village street, or on an estuary when used as a hydroplane, or on a ship's deck.

A further object is the maintenance of a more balanced distribution of load and in 35 respect to the supporting plane.

A further object is the attainment of a parachute, whereby the airplane will descend without danger, if for any reason the propeller or propellers are stopped during 40 flight.

A further object is that my airplane may be partly collapsed and then be readily driven or transported in a relatively narrow street or if used as a hydroplane among craft 45 in a harbor.

Other objects will appear from the drawings and description which follow.

These objects I attain by constructing my supporting plane of three or more sections 50 consisting primarily of a central plane and a wing on each side thereof and hinged to the said central plane and attaching operating cables from each wing to the car body which body is also supported from the central plane, 55 and I thereby effect the distortion of one

of the side wings whenever the car body is displaced from its normal center so as to decrease the supporting surface on the high side. Stability is further attained by the weight of the supported body or other 60 structure or load in such a way that the entire gravitational effect of the load is exerted on either side that may be relatively higher at any moment of time, thus always tending to pull the plane to a horizontal position.

Side slipping is prevented by side walls relatively vertically disposed with respect to the central plane, and longitudinal with the frame, and above the center of gravity of the 70 load.

An adjustable damper located between the side walls is provided to enable an obstruction of any desired amount to be introduced by the operation to counteract any tendency 75 to nose diving or tail slipping.

The car body I suspend from the central frame and from each side of the center thereof, and attach tension wires from the said body to the said side wings. At right 80 angles to the said central plane and longitudinally therewith I provide side wings as recited above and between these I prefer to mount a damper plane normally horizontal but with means whereby the said damper 85 may be inclined in either direction so as to present a surface at an angle with the said central plane as may be desired by the operator.

I prefer to use two engines located one 90 at each end of the car body and provide operator compartment and passenger space therebetween.

My airplane will act as a parachute at any time that the driving force is removed, due 95 to the supporting plane, wings, side walls, and central damper when the latter is turned at right angles to the central plane. By turning downward the side wings, against the side walls, the width of my airplane is 100 instantly greatly reduced, thus allowing its landing, driving or transportation in a narrow way or street.

By constructing the lower parts of the body or frame as pontoons my airplane may 105 be used as a hydroplane.

By referring to the accompanying drawings my invention will be made clear.

Figure 1 is a side view in perspective of an airplane of my invention.

Fig. 2 is a longitudinal cross section through my airplane showing the same in side elevation and with particular reference to the operating cables and the preferred shape of the supporting plane.

Fig. 3 is a plan view of the frame and lower structure of the plane in Fig. 2 with the side planes dotted in to better show the operation of the dampers and adjustable end planes.

Fig. 4 is a longitudinal view of one of the side wings showing the warping of the wing due to the operation of the forward cable only.

Fig. 5 is a part cross section and part perspective view through the plane, wings, vertical partitions, frame, and supporting platform, and showing particularly the suspension of the latter on the line V—V of Fig. 1.

Fig. 6 is a detail showing one of the side wings distorted and the air passage thereby created between the central plane and side wings.

Fig. 7 shows in reduced cross section the parts set forth in Fig. 5, wherein one of the wings is distorted as for the purpose of maintaining stability.

Fig. 8 is similar to Fig. 7 but with the other wing distorted in order to bring the plane back into its horizontal position.

Fig. 9 shows in detail the track means for limiting the movement of the body.

Throughout the figures similar numerals refer to identical parts.

In the frame structure, which I have shown in these figures, there are but three frame panels indicated by the numerals 1, 2, and 3, which in turn are joined together by horizontal members 4, 5 on the bottom and corresponding top members 6 and 7. Stretched across the top of the frame is a central plane 8 which I prefer to make of wave form as indicated in Fig. 2, and on each side of said central plane are the wings 9 and 10, which are hinged at suitable intervals to the frame as by hinges 11, 12, 13 and 14, and I prefer to set the hinged pivots out from the main frame, so that when either of the wings, as wing 9 in Fig. 6, is pulled away from the horizontal, either by the side swinging of the platform 15 from the horizontal position or by the operation of the cable 16 by the operator, and which may be actuated from the windlass as 17 (see Fig. 5) there will be permitted a flow of air from the space between the wing 9 and the plane 8 through the clearance space 18 (see Fig. 6), thus resulting in a reduction of the supporting power of the wing 9 as compared with the wing 10. Springs as 19 are provided to normally retain the wings in a horizontal position, such that they form in effect a continuation of the central plane 8. Along the sides of the frame and adjacent to the top plane 8, I provide depending side walls, as

20—21, and I provide centrally and having its axis at right angles to the direction of flying a rotatable damper plane 22. It will now be observed that by setting the damper plane 22 at right angles to the position shown in Fig. 1, there will be pockets formed such that the central plane 8, damper 22, and side walls 20—21 will form a parachute to support the entire structure against too rapid descent, and the center of gravity being substantially close to the platform or body, and well below the supporting surface of the parachute, will prevent any rapid or dangerous descent of the structure. The platform 15 is suspended from the side frames at any number of points by guy wires as 23, 24, 25, and 26. As long as the airplane retains its horizontal and vertical alignment the platform 15 will be supported by all of these guy wires equally. If, however, the plane lists from the vertical ever so little, as indicated for example in Fig. 8, the platform or body 15 will swing to the right and the control cable 16 will thereupon pull the wing 9 away from the surface of the central plane 8, reducing the air support of the plane on the left hand side until it has righted itself, when the wing 9 will again assume the position as indicated in Fig. 5, as the platform 15 recovers its vertical alignment and the plane becomes horizontal.

A distortion from the vertical in the opposite direction will result in the displacement of the wing 10 with respect to the plane 8, followed immediately by the correction of alignment, and it will thus be seen that stability is automatically maintained by the action of the platform 15, and the co-operative action of the side planes through their controlling cables as 16 and 27. I prefer to provide on the ends of the platform 15 a traveling member and a quadrant whereby the movement of 15 may be retained at all times within the limit of the movement of the member of the quadrant. This member is shown by the numeral 28 and the quadrant by the numeral 29, which latter may be supported in any suitable way from the frame as by the guy wires 30, see Fig. 9. At 31 I provide a front rudder or guiding plane (see Figs. 2 and 3), and at 32, 33, vertical steering planes or rudder, and at 34 a tail guiding plane, which latter I prefer to cut away as indicated in Fig. 3, and to pivot it at 35, 36 respectively, with rudder planes 32—33, so that the plane 34 swings between the said rudder planes to any desired angle from the horizontal, pivoted on the outer edges of the rudder planes 32—33 and at the same time permits a freedom of movement of the rudder planes 32—33 independent of said tail plane.

Operating cables of the plane 34 are shown at 37 and 38, which may be actuated from the operator's platform as at 39. At 40 is

provided operating means from which suitable operating cables are connected to the damper plane 22; at 41 a controlling means of the plane 31; at 42 controlling means for 5 the rudder planes 32—33; at 43 controlling means for the side wing cables 44—45, whereby the front portion of either of the side wings may be distorted independently of the rear portion (see Fig. 4), and at 17 10 controlling means for the rear cables 16 and 27 of the side wings, whereby they may be operated if desired independently of the front portions of the side wings. The operating means 43—17 may be connected together 15 as by gears or chain and sprocket, so as to produce simultaneous action by the control cables 44—16 and also if desired simultaneous action of the cables 45—27.

I claim:

20 1. In an airplane a supporting plane parallel with the line of flight and consisting of a central member bounded on each side by a movable wing, a load suspended from the central member and connections 25 from each wing to said load whereby the swinging of the load upon the tilting of the machine distorts one of the side wings to right the machine.

2. An airplane as set forth in claim 1 having a depending wall on each side of the central member and longitudinally disposed and adjacent said central member.

3. An airplane as set forth in claim 2, wherein a pivoted damper plane extends between the side walls, and operating means 35 for said damper plane.

4. An airplane as set forth in claim 3 and having independent means for displacing either of the side wings with respect to the 40 central plane.

5. An airplane as set forth in claim 1 wherein the load comprises a longitudinally disposed member relatively heavy, suspended from a plurality of points on each side 45 of said central plane, and having a plurality of connections to each wing, whereby the swinging of one end of said longitudinally disposed member warps one of the wings to right the plane.

50 6. An airplane as set forth in claim 5 and having a depending wall on each side of the central member and longitudinally disposed and adjacent said central member.

7. An airplane as set forth in claim 6, wherein a pivoted damper plane extends between the side walls, and operating means 55 for said damper plane.

8. An airplane as set forth in claim 7 and having independent means for displacing either of the side wings with respect to the 60 central plane.

9. An airplane comprising a box type frame and having thereon a supporting plane comprising a central plane and a wing on each side thereof and hinged thereto and 65 a body longitudinally suspended beneath and from the central plane and connections from said body to said side wings, whereby upon a tilting of the airplane the swinging movement of the body actuates the upper 70 wing to retain said wing in a substantially horizontal position.

10. An airplane as set forth in claim 9, having a depending wall on each side of the central member and longitudinally disposed 75 and adjacent said central member.

11. An airplane as set forth in claim 9, wherein a pivoted damper plane extends between side walls depending from the central plane, and operating means for said damper 80 plane.

12. An airplane as set forth in claim 9, and having independent means for displacing either of the side wings with respect to the 85 central plane.

13. An airplane as set forth in claim 1 wherein the suspension of the load from the central member is by tension cables from both sides of the load to both sides of the central plane.

14. An airplane as set forth in claim 14 wherein said cables are connected at points on the central member farther apart than their points of connection to the said load.

15. An airplane as set forth in claim 14 95 wherein said cables are connected at points on the central member farther apart than their points of connection to the said load, whereby on the airplane tilting sidewise the point of suspension for the load and on the 100 central member automatically shifts to the high side.

In testimony whereof I have hereunto set my hand at San Francisco, California.

NORMAN R. SMITH.
